Application May 13, 1936, Serial No. 79,559

7 Claims. (Cl. 51—9)

1

This invention relates to abrading apparatus and more particularly to mechanical apparatus for propelling abrasives at abrading velocities.

Abrasive throwing wheels having bladed rotors have been known in the art for many years, and although they are now going into rather wide use they are open to the objection that valuable time is lost changing blades. The blades of abrasive propelling rotors must be made removable, so that they may be replaced when they have worn out, and yet must be held so securely that they will resist the tremendous centrifugal force exerted when the wheel is operating.

Also, in centrifugal abrading machines where-in the abrasive is fed to the blades through an opening in a central feeding device and the discharge is directionally controlled, it has been found that when large volumes of abrasive are fed to the machine the discharge stream widens out to such a degree as to render the same undesirable for certain installations, for instance when the machine discharges into a work tumbling barrel or drum.

The centrifugal abrading machines in use today are open to the further disadvantage that the blades wear out rapidly, which entails high maintenance costs. The blades would have a reasonable life if the wear occurred uniformly throughout the width of their propelling surfaces, but it has been found that through casting or other inaccuracies, substantially all of the abrasive admitted to each blade will take a course in a localized stream thereover when the blades are first placed in use, and as time goes on the blades will be deeply worn in this particular region with the result that all of the abrasive traversing the blade will take this course, producing rapid break-down of the blade.

It is a primary object of this invention to provide an abrading machine blade assembly that securely holds the blades in place and yet permits them to be removed and replaced in a minimum of time.

It is a further important object of the invention to provide a novel blade assembly for abrading machines that will hold all of the blades securely in place while the machine is operating, will permit easy and rapid removal and replacement of the blades when they wear out and which will also permit the blades to be removed and replaced in the machine in a different relationship to present different surfaces to the abrasive when certain of their surfaces have become worn.

A further object is to provide, in an abrading machine having a bladed rotor for propelling the

2

abrasive, a novel blade mounting assembly which will securely hold the blades in place and will not work loose during operation of the machine, and which will permit the blades to be quickly and easily removed from the rotor.

It is another object to provide a feeding mechanism for an abrading machine which will deliver abrasive to the inner ends of the propelling blades in such manner as to enable the machine to deliver a concentrated stream of abrasive, even when abrasive is fed thereto in large volumes.

A further object is to provide an abrading machine with means for throwing the abrasive "splash" back into the blades in such a region as to cause the abrasive to discharge from the blades as though the splash had not occurred.

A still further object is to provide abrading machines with blades having means for causing the abrasive to take definite paths thereover, for rendering uniform the wear that occurs thereon.

My invention also aims to provide an abrading machine with propelling blades which are so formed as to impart wear and friction reducing action to the abrasive as it passes thereover.

It is also an object to devise blades for use in an abrasive throwing rotor which will produce a minimum blocking action and consequently a minimum splashing action when abrasive is fed over their inner ends.

Another object is to provide an abrading machine with an adjustable feeding device and to provide the adjusting device with means for making it possible to disassemble the parts without disturbing the adjustment of the device.

A further object is to refine and improve certain detailed features of centrifugal abrading machines.

Further objects of the invention will become apparent as the specification proceeds in connection with the annexed drawings, and from the appended claims.

In the drawings:

Figure 1 is a side elevational view of an abrasive propelling rotor equipped with the blade assembly of this invention, with parts thereof broken away in order to more clearly illustrate the structure involved.

Figure 2 is a view looking at the wheel of Figure 1 from the right-hand end of that figure, with parts broken away for clarity of illustration.

Figure 3 is an enlarged fragmental sectional view illustrating the manner in which the blades cooperate with their locking screws.

Figure 4 is an isometric view of one of the blades of the invention.

Figure 5 is a transverse sectional view taken on the line 5—5 of Figure 1, looking in the direction of the arrows.

Figure 6 is a fragmental longitudinal sectional view of the machine shown in Figure 1.

Figures 7 and 8 are transverse sectional views of modified forms of blades forming part of my invention.

Figure 9 is a longitudinal sectional view of a further form of blade of the invention.

Figure 10 is a longitudinal sectional view of a further modified form of blade of the invention.

Figure 11 is an end view of the blade shown in Figure 10.

Figure 12 is a longitudinal sectional view of a still further modified form of abrasive propelling blade.

Figure 13 is a rear view of a modified form of centrifugal abrading machine also forming part of my invention and which shows a modified form of adjusting mechanism and indicates an inspection and service door for the wheel housing.

Figure 14 is a longitudinal sectional view of the machine shown in Figure 13 and is taken substantially on line 14—14 of that figure.

With continued reference to the drawings, wherein like reference characters have been employed to designate like parts throughout the several views thereof, the rotor is designated at 20 R, and it is rigidly secured to a shaft 10. Shaft 10 is mounted for rotation in any desired bearing assembly (not shown) and rotor R carries a plurality of abrasive propelling blades B. Blades B terminate short of the center of the rotor to define a central abrasive admitting space in 25 which an abrasive feeding device F is supported for feeding a stream of abrasive over the inner ends of blades B.

The feed device will be presently described, and it effects directional discharge of the abrasive thrown from the wheel, but it is to be understood that insofar as the blades and blade mounting are concerned, the invention is not limited to a particular feeding device but may be applied to any type of abrading machine. For instance, feeding device F may assume the form of a pipe or a chute for dumping the abrasive into the central space and effecting a three hundred and sixty degree discharge of the abrasive. Also, blades B have been shown as four in number, but it is to be understood that the invention is applicable to rotors having more or less than four blades.

Secured to the face of rotor R, by a plurality of countersunk screws 11, are four symmetrically arranged plates 12. The radial edges of plates 12 are provided with bevelled faces 13, and the adjacent edges of each pair of plates define a dove-tail groove 14, as seen in Figure 1.

Blades B are provided with correspondingly dove-tail shaped bases to fit in grooves 14, and have inclined faces 15 cooperating with walls 13 of plates 12. The inclined faces 15 of blades B merge into abrasive-propelling surfaces 16 provided on each side of the blade. As seen in Figure 1, inclined faces 15 merge with plates 12 in a region spaced from their propelling surfaces 16, with the result that the abrasive moving outwardly over surfaces 16 is maintained out of abrading contact with plates 12, which are permanent parts of the machine. The free edges of blades B are each provided with a flange or ridge 17 to confine the outwardly moving abrasive to surfaces 16.

The blades are accordingly mounted for guided

movement toward and away from the axis of the rotor, and although grooves 14, which constitute the guideways, are shown as being disposed substantially radially, it is to be understood that they may be inclined forwardly or rearwardly with respect to the direction of rotation if desired without departing from the spirit of the invention.

The means employed for restraining blades B against outward movement preferably takes the form of a screw 18, threaded into rotor R adjacent the outer end of each guideway 14. Each screw 18 is provided with a hex head 19 which projects into a recess 21 in the base of each blade B and cooperates with a wall 22 thereof to positively arrest outward movement of the blades. The flat sides of head 19 provide a large bearing surface for wall 22 and also prevent screws 18 from working loose in operation.

Referring to Figures 2 and 3, wall 22 and its opposite wall are spaced apart a distance which is greater than the greatest diameter of hex heads 19, with the result that blades B can be slipped into place in grooves 14 and screws 18 turned up until they assume the position shown in Figure 3. Blades B may then be pulled outwardly until their walls 22 abut one of the flat sides of hex heads 19 as seen in Figure 3, or they may be left in their inner positions because when the rotor is started centrifugal force will bring them into cooperating relationship to screws 18. The inherent friction present between blades B and their guides may be relied upon to restrain them against inward movement when the rotor is subsequently stopped; but if desired, spring means, taking the form of a split resilient ring, encircling feed device F and engaging the inner ends of the blades, may be used to positively hold them in engagement with screws 18.

Although screws 18 may be provided with any suitable formation to permit them to be turned home with a wrench, they are preferably internally formed with a hex socket 23 in order that the screws may be so dimensioned as to lie flush 30 with the rear surface of rotor R when they are turned home. It is not necessary to turn screws 18 into a final position where a flat side of hex head 19 will be disposed in parallelism with wall 22 of recess 21 because the forces set up by rotation of the wheel will cause the blades to work screws 18 into the relationship shown in Figures 2 and 3. Screws 18 are preferably designed, however, so that the faces of socket 23 and hex head 19 are disposed in registry, as seen in Figure 3, with the result that the relationship of the surfaces of hex head 19 to wall 22 of blade B may be determined by merely glancing at socket 23. Also, if a wrench of the type shown in dotted lines in Figure 3 is used, the relationship of the parts will be directly indicated by the position of the wrench handle.

If, however, the heads of screws 18 are so dimensioned as to seat in the bottoms of recesses 21 when they are turned home it is unnecessary to take any particular precaution in installing the blades because screws 18 are thus automatically stopped in approximately proper position and will assume proper position when the wheel is started.

As seen in the drawings, when the screws are turned home a clearance exists between their shoulders and the parts of blades B defining recesses 21.

Although a particular form of locking assembly has been illustrated, it is to be understood that

other forms of locking devices, which themselves are locked by the blades, may be used without departing from the spirit of this invention. For instance, instead of using screws 18, simple pins, having formations at their ends for interlocking engagement with the blades when the latter are slid outwardly, may be used if desired. Moreover, hex head 19 may be made with more or less than six sides if desired. For instance, square headed screws may be used if desired.

Referring now to Figure 4, each blade B is provided with two recesses 21 in its base and it is therefore symmetrical in form. The base of the blade also may or may not be cored out, as at 24. With the wheel rotating in the direction indicated in Figure 2, the abrasive is picked up by and discharged from the counter-clockwise surfaces 16 of blades B. By reason of the symmetrical design of blades B it is possible to remove the blades when they have become partially worn and reverse them end-for-end and thereby bring a new propelling surface into cooperation with the abrasive. The worn surface is accordingly placed on the clockwise side of each blade. When the new surface has become worn the blades are of course discarded.

If an uncored blade is employed, it is to be understood that a single recess 21, located mid-way between the ends of the blade, may be used. Also, two screws 18 may be employed to hold each blade of the present invention in place, but it has been found that one screw is adequate, and the term "a screw" or "a securing device" as employed in the appended claims is intended to embrace the use of one or more screws 18 or their equivalents.

As seen in Figures 1, 5 and 6, feeding device F comprises a cylindrical member 26 having an abrasive discharge opening 27 and a plurality of external teeth having faces 29 and 31. Cylindrical member 26 is supported for adjustable rocking movement about the axis of the rotor upon a support S. Cylindrical member 26 is provided with a pair of studs 33, which project through a pair of arcuately-shaped openings 34 provided in support S. A pair of nuts 35 are threaded on studs 33 and are operable to clamp feed device F to support S in any desired adjusted position, for varying the direction of discharge from the wheel.

Support S is provided with a spout portion 37 through which the abrasive may be admitted to the wheel and the abrasive fed through the spout is introduced into the center of a hollow impeller 38 having a plurality of blades 39. The forward face of each impeller blade 39 is concave in transverse section, and by reference to Figure 5, it is seen that each impeller blade inclines outwardly and rearwardly with respect to the direction of rotation of the rotor.

The impeller is provided with a base portion 41 which is releasably clamped to the end of the rotor by means of a cap screw 42 or the like. The impeller is preferably assembled in the machine so that each impeller blade is advanced a predetermined degree with respect to its propeller blade B. The right-hand side wall of member 26 (Figure 6) is provided with notches (not shown) for allowing the impeller to be removed therefrom.

It has been found that when a particle of abrasive leaves the tip of an abrasive propelling blade its direction is determined by the respective magnitudes of its radial outward velocity component and its tangential velocity component.

I have found that by inclining the blades of the impeller rearwardly, so as to diminish the tangential component and simultaneously increase the radial component, it is possible to make the abrasive discharge through opening 27 in container 26 to take the general path indicated by the arrows 45 in Figure 5. The abrasive discharged through opening 27 in this manner assumes a more concentrated stream. The abrasive is then picked up by the inner ends of blades B passing closely adjacent opening 27 and is smoothly and continuously accelerated until it reaches the blade tips, where it is discharged downwardly in the approximate direction indicated by the arrows 47. If it is desired to make the machine discharge in a direction other than that shown, nuts 35 may be loosened and cage 26 rocked in the proper direction to effect the desired discharge. In view of the fact that the point at which the abrasive will be discharged from the machine depends upon the angular location of opening 27; the speed of the wheel; and the length of the blades, it is apparent that confining or concentrating the angular range over which admission or pick-up occurs will simultaneously limit or reduce the angular region over which discharge from the blade tips occurs. It is impractical to achieve this result by reducing the circumferential dimension of opening 27 because to do so would seriously reduce the capacity of the machine.

It has been found that in abrading machines of this character, especially when large quantities of abrasive are fed thereto (from 15 to 25 thousand pounds per hour), a considerable portion of the abrasive is struck by the inner surfaces 48 of the blades, with the result that it rebounds back against the exterior wall of container 26. This rebounding abrasive, when containers having smooth exterior walls are used, is rebounded off the container and back into the path of the inner ends of blades B at points angularly remote from opening 27, with the result that the discharge point of such rebounding abrasive occurs a considerable distance from the discharge point of the main body of the abrasive.

By providing teeth on the external surface of the container, the rebounding abrasive, indicated by the arrows 51 in Figure 5, strikes tooth faces 31 and rebounds back into the path of the inner ends of blades B at points not remote from the angular location of opening 27, with the result that this rebounding abrasive is discharged from blades B along with the main body of the abrasive discharge.

Although I have for sake of providing a compact assembly, provided the rebound teeth directly on the outside of conduit 26, it is to be understood that if desired, particularly if a plain feed pipe with no impeller is used, the rebound teeth may be formed in a separate member or members without departing from the spirit of my invention.

It is apparent that by inclining the impeller blades rearwardly so as to obtain a more nearly radial discharge of the abrasive through opening 27, and by providing the exterior of casing 26 with teeth, the concentration of the discharge of abrasive from the machine is greatly improved. In some installations it may not be necessary to have an extremely narrow band of abrasive and in such case it will only be necessary to employ one of these features, and the appended claims

are therefore intended to cover the two features either singly or in combination.

In the present instance, the impeller vanes are equal in number to and are advanced with respect to their propeller blades B, with the result that a concentration of the stream emitted through opening 27 occurs each time a blade B comes into abrasive pick up position, with the result that the discharge concentrating action is further enhanced.

In Figures 7, 8 and 9 I have illustrated modified forms of blades that may be used with the machine that has just been described. In these figures the blades are generally the same in form as those shown in Figures 1 to 6 inclusive and therefore like reference characters have been employed to designate corresponding parts throughout the several views.

In Figure 7 the propelling surfaces of blade B¹ are of corrugated form so as to provide a plurality of valleys 55. It has been found that when a blade of this character is employed, the abrasive, which is introduced on the inner ends of the blades, is caused to take a plurality of definite paths outwardly thereover, with the result that uniform distribution of the abrasive is maintained until it leaves the tips of the blades. Avoidance of localized wear is accordingly achieved.

In Figure 7, the valleys 55 on one surface are aligned with the valleys 55 on the other surface of the blade, with the result that the blade is of non-uniform section and accordingly it may be hardened at some points more than others during manufacture. Another factor which increases the life of this blade over the ordinary plane surface blade is the increase in area obtained by corrugating the surfaces of the blade. Increasing the area increases the amount of material that must be worn away before the blades need be discarded.

In Figure 8 I have shown a blade B² identically similar to that shown in Figure 7 with the exception that valleys 56 in one surface are disposed in alignment with the corrugations of the other surface, with the result that the blade is of uniform section and may accordingly be uniformly hardened throughout.

In Figure 9 there is disclosed a somewhat different form of blade B³ which is provided with a transversely corrugated abrasive propelling surface 58. In this form of the invention, as the abrasive travels outwardly over the corrugated surface it only strikes the tops of the corrugations, and in view of the fact that it only contacts the blade surface a limited number of times before it is discharged from the blade tip, the total wear is reduced. If desired, a combination of the forms of blades shown in Figures 7 and 8 and Figure 9 may be used. For instance, corrugated blades shown in Figure 7 may be provided with transverse corrugations that lie flush with or project slightly above the outwardly extending corrugations so as to confine the abrasive to definite outward paths and yet to cause it to strike the blade a limited number of times as it travels outwardly.

In Figures 10 and 11 I have shown a modified form of blade B⁴, wherein the blade is provided with a flat abrasive propelling surface 61 and a bevelled inner edge 62. The blade of this form of the invention is irreversible and hence is provided with only one side flange 63 which, as seen in Figure 11, provides an inclined abrasive guiding wall. The blade is also provided adja-

cent the junction of abrasive propelling surface 61 and the base of the blade with a longitudinal groove 64 for the purpose of providing a definite abrasive confining or guiding wall so as to prevent abrasive from abrading dovetail groove forming plates 12.

With blades B⁴ installed in the wheel so as to rotate in the direction indicated in Figure 10, it is apparent that as the abrasive is discharged from opening 27 in cage 26, the abrasive ribbon will be sharply cut off. That is, there will be an abrupt break in the abrasive ribbon as all of the abrasive preceding the break will travel outwardly over propelling surface 61 and the succeeding part of the ribbon will not contact the blade at all by reason of the fact that wall 62 is cut away sufficiently so that it moves away or recedes too rapidly for the outwardly moving abrasive to strike it.

In Figure 12 I have illustrated a blade similar to that shown in Figures 10 and 11, but in this form of the invention the blade is provided with a slightly bevelled inner end 66 and a similarly bevelled outer end 67. In view of the fact that this form of blade is symmetrical it may be reversed in the same manner as the blades shown in Figures 1, 2 and 3. Although the bevel of the inner and outer ends of the blades shown in Figure 10 are not very great, it has been found that with the usual speed of the abrasive issuing from slot 27 in the impeller cage the abrasive travels only approximately $\frac{1}{8}$ of an inch while the blade is traveling through the angle defined by the inner ends of the blades, and therefore it is only necessary to bevel the blade parts to this extent in order to prevent the abrasive from striking the bevelled face.

In Figures 13 and 14 I have illustrated a modified form of machine wherein the impeller cage is supported for adjustment in a different manner. In this form of the invention I have shown a housing as being associated with the machine because certain parts of the mechanism are attached thereto.

The rotor is here enclosed in a housing H having an inner liner 71. As seen in Figures 13 and 14, support S¹ is of somewhat different form than that shown in Figure 6 and it is provided with a flange 72 which is secured to housing H by a plurality of screws 73 or the like. A plurality of shims 74 are preferably disposed between flange 72 and housing H for properly positioning support S¹ and the feeding device with respect to the rotor in the mechanism.

Housing H is provided with an opening 76 of elongated formation extending substantially radially with respect to the machine axis. Opening 76 is closed by a closure plate 77 which is detachably held in place by a screw 78 threaded into a yoke member 79, which is in turn slotted and held in place on the machine by a pair of headed stud members 81.

By loosening screw 78 yoke member 79 may be slipped out from under the heads of studs 81 and the closure 77 removed. A screw driver may then be employed to remove screws 71 so as to allow plate 12 to be removed from the rotor for servicing and the like. Also, opening 76 provides a convenient opening through which the condition of the blades may be observed.

Secured to the rear face support S¹ is an arcuately-shaped stop plate 82 having an arcuate slot 83 therein. Plate 82 is detachably clamped to support S¹ by means of a stud 84, which is fastened in support S¹ a nut 85 and a collar 86.

The ends of stop plates 82 cooperate with the cylindrical portions of nuts 35 in order to maintain cage 36 in proper angular relationship in the machine.

For instance, it has been found that the machine may be adjusted for a certain type of abrasive and maintained in this adjustment so long as the abrasive and the conditions under which the machine is used remain unchanged. When cage 26 is placed in this adjusted position, nut 85 is tightened and maintains stop plate 82 in a position determined by nuts 35. Therefore, when nuts 35 are removed and cage 26 replaced by a new cage, the cage must be installed in the machine in the correct angular relationship as nut 35, when they are threaded on the studs of the new cage engage stop plate 82 and bring the cage into correct position. In order to indicate the angular position in which the cage is rotated, I preferably provide flange 72 with indicia 87 which cooperate with a right-hand nut 35 (Figure 13) to indicate the position at a glance.

Although it is preferably to employ the blade assembly with a rotor having but a single disc to which plates 12 are secured, the invention is clearly applicable to rotors having two discs as the guideway and/or the blade locking assembly may be duplicated on each disc.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In an abrading apparatus, an abrasive propelling rotor mounted for rotation and providing a central abrasive admitting space, a feed device for introducing abrasive into said space, a stationarily mounted support having at least one arcuately shaped aperture, said feeding device having at least one securing device projecting through said arcuate aperture and operable to clamp said feeding device in a plurality of different positions upon said support, and a stop member releasably clamped to said support and having a portion cooperating with said securing device for insuring proper assembly of said feeding device upon said support, thereby permitting said feeding device to be removed and replaced without disturbing the adjustment thereof.

2. The abrading apparatus described in claim 1, wherein said securing device comprises a stud member fastened to said feeding device and a nut threaded thereon and engaging said support and said stop member.

3. The abrading apparatus described in claim 1, wherein said stop member comprises a member engageable with said securing device and having means securing it to said support for movement into a plurality of adjusted positions corresponding to the adjusted positions of said feeding device.

4. In an abrading apparatus, an abrasive propelling rotor mounted for rotation and providing a central abrasive admitting space, a feed

device for introducing abrasive into said space, means mounting said feed device for rocking movement into a plurality of adjusted angular positions about the axis of said rotor on a stationary support, means for securing said feed device in one of a plurality of adjusted angular positions with respect to said support, and means for compelling assembly of said parts in a predetermined relationship, said last-named means comprising an element having means for releasably clamping it to said support in a plurality of angular adjusted positions with respect to said support, said element being movable through a range of movement substantially equal to the range of movement of said feed device with respect to said support.

5. In an abrading apparatus, a rotor having a plurality of outwardly extending abrasive propelling blades mounted thereon, said blades terminating short of the axis of said rotor to define an abrasive admitting space, said blades being operable to pick up and propel abrasive admitted at a predetermined feeding zone in said abrasive admitting space, and stationarily supported means disposed in said abrasive admitting space for rebounding back toward said feeding zone any abrasive that may be improperly picked up by the inner ends of said blades, said means comprising a member having a plurality of angularly disposed rebound surfaces provided thereon and located adjacent the path of rotation of the inner ends of said blades substantially equi-distant from the axis of rotation of said rotor, said surfaces each being inclined at an obtuse angle with respect to a radial line intersecting said surface, said obtuse angles facing rearwardly with respect to the direction of rotation of said rotor.

6. The abrading apparatus defined in claim 5, wherein a generally cylindrical abrasive feeding device is disposed in said abrasive feeding space and said rebound surfaces are provided on said feeding device.

7. The abrading apparatus defined in claim 5 wherein a generally cylindrical abrasive feeding device is disposed in said abrasive feeding space and said rebound surfaces are provided on said feeding device, said abrasive feeding device containing a rotatable impeller having blades which incline outwardly and rearwardly with respect to the direction of rotation of said rotor.
